US0D1103631S

(12) **United States Design Patent** (10) Patent No.: **US D1,103,631 S**
(45) Date of Patent: ** Dec. 2, 2025

(54) **CHAIR**

(71) Applicant: **Haskell Office**, Bala Cynwyd, PA (US)

(72) Inventors: **Bruce Robins**, Philadelphia, PA (US);
John Myers, Columbus, OH (US);
Erin Leigh Olesen, Saugatuck, MI
(US); **Matthew R Ruster**, Zeeland, MI
(US); **Lucas Vinecki**, Hudsonville, MI
(US); **Timothy David Stoepker**, Grand
Rapids, MI (US); **Lucas Matthew
Schupbach**, Paw Paw, MI (US)

(73) Assignee: **HASKELL OFFICE**, Bala Cynwyd,
PA (US)

(**) Term: **15 Years**

(21) Appl. No.: **29/894,438**

(22) Filed: **Jun. 9, 2023**

(51) LOC (15) Cl. **06-01**

(52) U.S. Cl.

USPC **D6/334**

(58) **Field of Classification Search**

USPC D6/334-336, 338, 341, 349, 355,
D6/364-366, 374-376, 379, 380, 705.6,

D6/16, 716.7; D3/306

CPC A47B 41/00; A47B 41/02; A47C 7/002;

A47C 7/006; A47F 5/01

(57) **CLAIM**

The ornamental design for a chair as shown and described.

DESCRIPTION

FIG. 1 is a front perspective view of the chair of the present invention.

FIG. 2 is a top view thereof;

FIG. 3 is a right-side view thereof;

FIG. 4 is a front view thereof;

FIG. 5 is a left-side view thereof;

FIG. 6 is a rear view thereof; and,

FIG. 7 is a bottom view thereof.

In the drawings, the broken lines show portions of the chair that form no part of the claimed design.

1 Claim, 7 Drawing Sheets
